UNITED STATES PATENT OFFICE.

AUGUSTE DUTREUX, OF ISSY LES MOULINEAUX, FRANCE, ASSIGNOR TO SOCIÉTÉ ANONYME POUR L'ECLAIRAGE ELECTRIQUE DES VÉHICULES, OF ISSY LES MOULINEAUX, FRANCE, A CORPORATION OF FRANCE.

ELECTRIC STARTING SYSTEM FOR INTERNAL-COMBUSTION ENGINES.

1,352,794.

Specification of Letters Patent. Patented Sept. 14, 1920.

Application filed February 17, 1917. Serial No. 149,262.

To all whom it may concern:

Be it known that I, AUGUSTE DUTREUX, engineer, of 26 Rue J. J. Rousseau, at Issy Les Moulineaux, Seine, France, citizen of the French Republic, have invented certain new and useful Improvements in Electric Starting Systems for Internal-Combustion Engines; and I do hereby declare the following to be a full, clear, and exact description of the invention, such as will enable others skilled in the art to which it appertains to make and use the same.

In the systems generally employed for the electric starting of combustion engines complicated switches are provided, requiring numerous wires and interrupters for conducting the current to the electric motor or for insuring the necessary operations for starting the motor, above all when the motor is designed to serve also as a lighting generator.

Where four-pole machines are employed, furnished with armature windings in such a manner that they can operate either with two or four brushes, it has been suggested to use two brushes for generator operation, the other two serving for motor operation; the last pair of brushes are movable, can make contact with the commutator in order to start the internal combustion engine, and can then be raised when the starting has been accomplished and the motor operates as a generator.

This system, which is very ingenious as it dispenses with auxiliary apparatus, has the great objection that if the internal combustion engine does not start instantaneously a current varying from 100 to 200 amperes is broken between the commutator and the brushes which serve for the starting operation. The surface of the commutator deteriorates, therefore, in a very short time by reason of the sparking.

The present invention has for its object to provide a system which avoids this objection and consists in breaking or establishing the starting current between each brush and an auxiliary contact with which it is provided, after the brush is put into contact with the commutator. Consequently, at the time when the brushes are either brought into contact with the commutator or disengaged therefrom no current is made or broken between the brushes and the com-

mutator, and the latter does not become deteriorated.

The accompanying drawings show by way of example a constructional form of apparatus for carrying out in practice the system according to the invention.

Figure 1 is a complete diagram of an arrangement comprising a dynamo electric machine, a voltage regulator, a make and break switch, also showing a constructional apparatus by which the invention can be carried into practice.

Fig. 2 is a plan of the apparatus for raising the brushes.

Fig. 3 is a section on the line A—B, Fig. 2.

Fig. 4 is a section on the line C—D, Fig. 2.

Fig. 5 is a section on the line E—F, Fig. 2.

Fig. 6 is a section on the line G—H, Fig. 2.

In Fig. 1 is indicated at 1 the rotatable armature of the dynamo electric machine, 2 and 3 are fixed brushes serving for the operation as a generator, 4 and 5 indicate shunt field windings, 6 and 7 are series field windings. The voltage regulator indicated at 8 comprises a thick wire coil 9 and a thin wire coil 10. These coils act on an armature (not shown) controlling the contacts 11 and 12 which make and break a short circuit across the terminals of a resistance 13 in series with the field windings. A fuse 14 connects the regulator to the make and break switch 15, which also comprises two coils, a fine wire coil 16 and a thick wire coil 17 acting on the armature controlling the contact 18 which connects the dynamo in parallel with the battery 19 and the lamps 20. The switching apparatus shown in Figs. 1, 2, 3, 4, 5 and 6 is in its starting position, the brushes 21 and 22 which serve for the operation of the machine as a motor being in contact with the commutator. These brushes are insulated in two holders 23 and 24, secured to the ends of two levers 25 and 26 pivoted on pivots 27 and 28. The pivots 27 and 28 also serve as pivots for two arms 33 and 34 (Figs. 2 and 5) which, by means of two plate springs 37 and 38, support two contact fingers 35 and 36.

The brushes 21 and 22 are pressed against the commutator by means of springs 29 and 30, shown in Fig. 2, one end of each spring being fixed in holes 31 in the levers 25 and 26. The other ends of the springs are secured in two holes 32 provided in the levers

- 33 and 34. Consequently the springs hold the two contact fingers 35 and 36 pressed on the carbon brushes 21 and 22. These fingers are connected to the terminals 41 and 5 42 of the battery 19 by means of the shunts 39 and 40, which are insulated by beads. The two arms 33 and 34 as well as the arms 35 and 36 are movable around the pivots 27 and 28.
- 10 A shaft 43 which can be operated from the exterior of the machine by means of a lever, the end of which is shown at 44, is formed to the shape represented, which will be seen by the successive sections, Figs. 3, 4, 15 5 and 6. A flat spiral spring 45 (Fig. 4) tends to make the shaft 43 constantly rotate backward. The levers 25 and 26 and 20 33 and 34 are provided with projections corresponding parts of the shaft 43 in such a manner that by rotating the shaft the relative positions of the levers 25 and 26 and 33 and 34 can be modified.

In the normal position the brushes 21 and 25 22 are withdrawn from the commutator by the shape of the shaft 43, the fingers 35 and 36 are not pressed on the brushes and the springs 29 and 30 are wound up.

If by means of the part 44 the shaft 43 30 is rotated from the outside through an angle of about 40° in the direction indicated by the arrow (Fig. 3), the springs 29 and 30, by reason of the shape of the shaft 43, shown in Fig. 6, causes the brushes to 35 engage with the commutator. By means of a further rotation of about 13° , see Fig. 3, the fingers 35 and 36 are, by reason of the shape of the shaft 43, as shown in Fig. 5, caused to press on the brushes 21 and 22, 40 thereby putting the battery in parallel with the dynamo machine.

By continuing the rotation through 37° (Fig. 3) a sufficient pressure will be obtained between the fingers 35 and 36 and 45 the brushes 21 and 22 to furnish an excellent contact.

The part 44 at this point abuts against the part 48 which is fixed to the dynamo (Fig. 3). The machine is driven by the 50 battery 19 and operates as a series motor by reason of the fields 6 and 7. The shunt fields 4 and 5 also add their fluxes to assist in starting, and no large current can pass by the brushes 2 and 3, the make and break 55 switch being open. When the internal combustion engine starts the make and break switch closes and the machine acts as a generator. If the external lever acting on the shaft 43 is then released the reverse operations to those above described take place in 60 the following order:—

1. After an angle of about 37° (Fig. 3) is described the current is broken between the fingers 35 and 36 on the one hand and 65 the brushes 21 and 22 on the other hand,

then after a further rotation of 13° (Fig. 3) the brushes are raised from the commutator without breaking any current, and the spring 45 returns the shaft 43 to its normal position, when the face 46 of the shaft 43 70 comes opposite the face 47.

2. The current furnished by the battery will be broken between the fingers 35 and 36 and the carbon brushes 21 and 22 if the internal combustion engine does not start, but 75 no current will be broken between these brushes and the commutator; consequently it is impossible for the latter to become deteriorated by reason of the sparking.

It will be understood that different apparatus can be employed for carrying out the system of the present invention.

The invention is not limited to the starting of internal combustion engines as it can be applied in a general manner to all suitably wound multi-pole dynamos, and can be carried out by any description of contact supplied from a battery of accumulators for the purpose of its operation as a motor, to be broken directly between the movable 90 brushes and the commutator so that all deterioration of the commutator is avoided.

I claim—

1. In an electric machine adapted to operate as a generator or a motor, a pair of 95 brushes for the same when operating as a generator, a second pair of brushes for the same when operating as a motor, means for putting the latter brushes in contact with the commutator and means operable to establish an electrical contact between said latter brushes and the accumulators, after said brushes have engaged the commutator, and subsequently operable to permit the movement of said brushes out of contact 100 with the commutator subsequently to breaking the contact between these brushes and the accumulator.

2. In an electric machine adapted to operate as a generator or a motor, a pair of 110 brushes for the same when operating as a generator, a separate pair of brushes for the same when operating as a motor, means for putting the latter brushes in contact with the commutator, contacts for establishing a circuit between said latter brushes and the accumulators, means subsequently operable to cause the engagement of the contacts with the brushes, said means being further operable to move the contacts out of 115 engagement with the brushes and finally the brushes out of engagement with the commutator.

In testimony whereof I affix my signature, in presence of two witnesses.

AUGUSTE DUTREUX.
